(57) **CLAIM**

The ornamental design for an air seal for paint can as shown and described.

DESCRIPTION

FIG. 1 is a top view of my design;

FIG. 2 is a perspective view from above of the design in FIG. 1;

FIG. 3 is a side view thereof;

FIG. 4 is a perspective view from below thereof;

FIG. 5 is a bottom view thereof; and,

FIG. 6 is a cross-section view of the design in FIG. 1, installed in a representative paint can.

The broken lines consisting of equal length dash lines in FIG. 6 depict parts of the paint can and paint contents that form no part of the claimed design.
